[57] **CLAIM**

The ornamental design for a biochemical card for use with an automated microbial identification machine, substantially as shown.

DESCRIPTION

FIG. 1 is a top plan view of a biochemical card for use with an automated microbial identification machine showing our new design;

FIG. 2 is a right side elevation thereof;

FIG. 3 is a bottom end elevation thereof;

FIG. 4 is a bottom plan view thereof;

FIG. 5 is a top end elevation thereof; and

FIG. 6 is a right side elevation thereof.
